UNITED STATES PATENT OFFICE.

JACOB C. LARSEN AND CLAUDE L. ORR, OF COLUMBUS, OHIO, ASSIGNORS TO THE BUCKEYE STEEL CASTINGS COMPANY, OF COLUMBUS, OHIO.

SIX-WHEEL CAR-TRUCK CONSTRUCTION.

Application filed February 10, 1927. Serial No. 167,316.

This invention relates to improvements in six wheel car truck constructions and contemplates side-frames, each comprising equalizing end members and a central 5 equalizing member flexibly connected at its ends with inner end portions of the end members, wear means being interposed at such flexible connections and the invention further contemplates three part side frames 10 and transverse bolsters, spring seats supported in bolster openings of the end side frame members, into which openings the bolsters extend and between which seats and the transverse bolsters, springs are interposed, said spring seats being provided with brackets to support inner brake hangers, outer brake hanger brackets being interlocked with the outer ends of the end members 15 of the side frames and secured by the same bolts which secure axle boxes to said end members.

In the accompanying drawings,—

Figure 1 is a side elevation of a six wheel truck embodying the improvements;

Figure 2 is a partial plan view;

Figure 3 is a fragmentary sectional view;

Figure 4 is a section on the line 4—4 of Figure 2;

Figure 5 is a sectional view showing one 30 embodiment of the wear feature between the side frame end members and the intermediate equalizing member;

Figure 5^a is a view in section at right angles to Fig. 5, and

Figure 6 is a sectional view showing a 35 modification of the construction of the wear feature.

In the drawings, only one side frame construction is shown but it will be understood that two such constructions are employed, one at each side of the truck. The side frames each comprises three members; two equalizing end members 1 and 2 and an intermediate or central equalizing member 3 with the ends of which latter the inner ends 40 of the end members 1 and 2 are flexibly connected,—the end members being so formed that their inner end portions will be disposed parallel with each other as shown in Figure 2 and connected respectively with the far 45 ends of the central or equalizing member 3. The inner end of each end member 1 and 2 is contracted in width as at 4 and enters between upwardly projecting flanges 5 on the 50 central member 3. A bolt 6 passes trans-

versely through the flanges 5 and freely through a transverse hole 7 in the end member 1 (or 2) and one of said flanges is provided with a lug 8 to be engaged by the angular head 9 on said bolt, the other end 60 of the latter being threaded to receive a nut 10, between which and a boss 11 on one of said flanges, a washer 12 is interposed. The free end of each end member 1—2 is provided with a socket 13 receiving a shank 14 65 on a wear block or plate 15 disposed at the inner end of each member 1—2. The horizontal web 16 at each end of the central member 3 is provided with a hole 17 which receives a shank 18 depending from a bottom wear plate or block 19 seated on said web 16 and engaged by the upper wear block or plate 15. Instead of providing a separate bottom wear plate or block, the web of the central member 3 at each end thereof 70 may be made thicker and constitute a wear pad to be engaged by the wear plate or block 15, such construction being indicated at 20, Figure 6.

Journal boxes 30 are secured by means 80 of bolts 31 and plates 32 to the respective end members of the side frame as shown in Figure 1 and the central equalizing member is provided with an integral axle box construction 33. Each of the end members 1 and 2 of the side frame is provided with a bolster opening 34 which receives the end portion of a bolster 35, the latter being located at respective sides and spaced from the central axle 36, the latter being 85 mounted in the axle boxes of the central or equalizing member 3 while the axles 37—37 at the ends of the truck being mounted in the axle boxes secured to the end members 1—2 of the respective side 90 frames. Spring seats 38—38 are located in the openings in the members 1 and 2 and interlockingly engaged with the latter as at 38^a. Between these seats and the transverse bolsters 35, springs 39 are disposed. 100 Each of the spring seats 38 is provided with an inwardly projecting bracket 40 adapted for the reception and support of a brake hanger, said brackets being located intermediate of the wheels 41—42—43. Located upon and having interlocking connection with the ends of the members 1 and 2 which project over the axle boxes carried by said members, are forwardly projecting brackets 44, the latter being secured in place 105 110

by the same bolts which secure the axle boxes to said members 1 and 2. The outer ends of the brackets 44 are made to project inwardly and constitute brackets for outer brake hangers.

The transverse bolsters 35 are provided with lugs 45 which engage the inner sides of the side frame members 1-2 respectively and the outer projecting ends of the transverse bolsters are connected adjacent each side frame by a bridge bar 46, the latter constituting guide means for the side frames and the transverse bolsters and the latter having guides 47-48 for the bridge bar 10 to maintain proper alignment of the latter.

A longitudinal bolster 49 is disposed intermediate the transverse bolsters and is provided at its respective ends with reduced portions 50 which enter the transverse bolsters 20 and said longitudinal bolster is formed with shoulders 51 to engage the transverse bolsters and maintain them in proper positions.

The upper and lower portions of each transverse bolster are provided with aligning 25 openings 52-53 and the longitudinal bolster is provided with an opening 54 which aligns with the openings 52-53 and through said openings a vertical pin or key 55 is passed and secured against displacement by means 30 of a cotter 56. By thus keying the longitudinal bolster at the ends thereof to the transverse bolsters, spaced relation between the transverse bolsters will be insured.

We do not, in this application, claim the 35 pin or key connection between the longitudinal and transverse bolsters, such construction being contemplated by application filed in the name of G. T. Johnson, filed February 10th, 1927, and designated by Serial No.

40 167,279.

Having fully described our invention what we claim as new and desire to secure by Letters-Patent, is:-

1. A six wheel truck in which each side 45 frame comprises two end members flexibly connected respectively with ends of a central equalizing member, and wear means interposed in the flexible connections between said end and flexible members.

2. A six wheel truck in which each side 50 frame comprises two end members flexibly connected respectively with ends of a central equalizing member, and wear means interposed in the flexible connections between 55 said end and flexible members, said wear means including wear members connected with the inner end portions of the end members of each side frame.

3. A six wheel truck in which each side 60 frame comprises two end members flexibly connected respectively with ends of a central equalizing member, and wear means interposed in the flexible connections between said end and flexible members, said wear means 65 interposed between each end member and

the central member, including two contacting wear members.

4. A six wheel truck in which each side frame comprises two end members flexibly connected respectively with ends of a central 70 equalizing member, and wear means interposed in the flexible connections between said end and flexible members, said wear means comprising pairs of wear plates, the plates of each pair being removably connected with end and central members respectively of the side frames.

5. A six wheel truck structure in which each side frame comprises two end members and a central equalizing member, each central member having pairs of parallel flanges receiving end portions of the end member between them and being loosely connected therewith, and wear means including a wear plate located between the flanges of each 85 pair on the central member and disposed between said end members and central members.

6. A six wheel truck each side frame of 90 which comprises three cooperating equalizing members, and wear devices interengaging with the end and central members and cooperable with each other.

7. A six wheel truck each side frame of 95 which comprises three cooperating equalizing members, each end member having a bolster opening containing a removable spring seat carrying brake hanger supports, journal boxes carried by the end members, and brake hanger brackets interlocked with 100 the end members over the journal boxes and extending forwardly and inwardly, said brake hanger brackets being secured to the same bolts which secure the journal boxes to the end members.

8. A car truck of the three axle type having side frames each comprising two end members having bolster openings and a central member having an integral axle box, 110 flexible connections and wear means between the inner end of each end member and the far end of the central member of each side frame, separate brake hanger brackets interlocking with the outer ends of the end members and secured to the latter and combined 115 spring seats and brake hanger supports arranged in the bolster openings of the end members of the side frames and interlocking engaging the latter.

9. A six wheel truck, each side frame of 120 which comprises three cooperating equalizing members, and wear devices interengaging with the end and central members relatively beyond the center of the central member with respect to each end member 125 and cooperable with each other.

In testimony whereof, we have signed this specification.

JACOB C. LARSEN.
CLAUDE L. ORR.
